UNITED STATES PATENT OFFICE

HENRY H. TALBOYS, OF MILWAUKEE, WISCONSIN, ASSIGNOR TO NORDBERG MANUFACTURING COMPANY, OF MILWAUKEE, WISCONSIN, A CORPORATION OF WISCONSIN

TURNTABLE SUPPORT

Application filed March 31, 1928. Serial No. 266,323.

This invention pertains to turntable supports designed more particularly for use in conjunction with portable mechanical shovels, cranes and like instrumentalities.

5 Mechanical shovels and cranes when operating under load necessarily place severe strains upon their turntable supports and the main object of the present invention is to provide a structure which, while standing 10 up under the work, is at the same time such as to insure ease of manipulation with consequent speed in handling.

For the purpose of description the turntable is shown and described herein in conjunction with a mechanical shovel but it is to be understood that the invention is not limited to such and the description of the shovel is to be taken as the equivalent of other mechanisms.

20 The invention is illustrated in the annexed drawings, wherein:

Figure 1 is a vertical longitudinal sectional view with the operating parts of the shovel proper shown in outline,

25 Figure 2 a top plan view partly broken away and partly in section of the shovel frame support and the truck upon which the same is mounted, and

Figure 3 an enlarged detail sectional view 30 illustrative of the means employed for introducing the balls into the raceway between the supporting frame and the truck frame and maintaining them in place.

The shovel mechanism, as such, may be 35 of any approved form, but preferably of that type wherein compressed air is employed as the power medium.

Such mechanism is denoted by 1 and is 40 mounted upon and secured to a turn-table or frame 2, which in the form shown is provided with a centrally disposed opening and at its periphery with an overhanging flange 3. It is also provided adjacent its periphery with an enlargement 4 in which is formed 45 one-half of a raceway for a series of supporting balls, the latter being designated by 5.

The truck frame is denoted by 6 and has 50 mounted in each end thereof axles 7 carrying flanged wheels 8 adapted to run upon a track

as 9, Figure 1. The axles are tied to each other by longitudinal side frames or bars 10, which in turn form the support for transverse bars or rods 11 and 12, which form the support for the rail clamps 13 of 55 any approved type.

A pair of stabilizing bars 14 and 15 extend transversely of the truck frame 4, said rods extending through the side bars 10 and being susceptible of manual longitudinal adjustment so that they may be projected to opposite sides of the truck. These bars will, in operation of the structure and the positioning of the car upon the track, take 60 against suitable supports at their outer ends, as for instance ties or the like placed thereunder, in order that the shovel as a whole may be kept from rocking and the rail clamps caused to maintain their proper position.

The truck frame 6, or more specifically the central casting or element thereof, is provided with a central opening into which the turntable or rotatable member extends. The truck frame is provided in its inner vertical 65 face with a semicircular raceway complementary to the raceway formed in the turn-table for the reception of the balls 5.

As will be best seen upon reference to Figure 3, the adjacent vertical faces of the members 4 and 6 are cut away as at 16 and 17 to provide a passage extending from the upper faces of said members for the introduction 70 of the balls 5 into the raceway.

After the raceway has been filled a cover 85 plate 18 is secured to the member 2 by tap screws 19, said plate being provided with a downwardly extending plug or projection 20 adapted to fill the upper portion of the groove or cut away part 17. It is to be noted that the 90 plug is not wide enough, however, to extend across into the opening 16 so that there is no interference between the parts when the turn-table 2 is rotated with reference to the truck frame 6.

A screw plug 21 is mounted in the cap piece 18 and affords a ready means through which lubricant may be introduced to the balls within the race.

Secured upon the outer face of the body 100

or member 6 is a circular rack 22 and a pinion 23, Figure 1, meshes therewith. Said pinion is formed upon the lower end of a rotatable shaft to which motion is imparted through a motor 24, the operation of which is under the direct control of the operator through means not shown.

In operation of the device, where the shovel (not shown), which is carried at the outer ends of the thrust beams or arms 25 (one only of which is shown) is forced into the material to be removed, or where the shovel is raised and extended over a car with a view of unloading the shovel, the tendency of the load is to tilt the turn-table and to place a downward thrust upon the balls adjacent one side of the table and an upward thrust at the opposite side, this thrust changing continually depending upon what operations are being performed by the shovel.

In practice the balls 5 are quite large, those of one and one-quarter inch diameter having been employed.

It has been found that under the severest service conditions the bearing holds up and inasmuch as it is a housed one little or no difficulty inheres from the presence of extraneous or foreign matter. Furthermore, the overhanging member 3 likewise houses the rack and the pinion is also substantially housed by giving the outer portion of the casting or turn-table 2 the contour shown in Figure 1, where, as will be seen, it is provided with an opening for the lower portion of the motor mounting with an incurved portion 26 which surrounds the pinion in spaced relation thereto.

As above noted the table construction is effective where the mechanism carried thereby is subjected to load outward of the table thereby placing a torsional strain upon the table bearing. Inasmuch as there is no king pin employed there is no chance for misalignment or cramping which commonly obtains when the king pin becomes worn.

What is claimed is:

1. In combination a truck frame having a circular opening formed therein; a supporting element for a shovel or similar instrumentality, said support having a depending portion extending into the frame opening, the opposing vertically disposed faces of said frame and element being contoured to form a ball raceway; and a series of balls mounted in said raceway, said balls forming the sole support for the supporting element and locking the same to the truck.

2. In combination a truck frame having a circular opening formed therein; a supporting element having a depending portion extending into the truck frame opening, the opposing vertically disposed faces of said opening and the adjacent face of the supporting element being contoured to form a ball raceway therebetween; a series of balls mounted

in the raceway, said raceway having an opening extending upwardly therefrom through which the balls may be introduced; and a removable closure for said opening.

3. In combination a truck frame having a circular opening formed therein; a supporting element for a shovel or similar instrumentality, said element having a depending portion extending into the truck frame opening the opposing faces of said circular opening and said element being contoured to form a ball raceway therebetween, said supporting element likewise having a depending flange extending around the same; a series of balls located in the raceway and locking the parts against relative tipping movement; a circular rack carried by the truck frame; a pinion meshing therewith; and means mounted upon the supporting element for driving the pinion.

4. In combination a truck frame having a vertically disposed internal face; a supporting element for a shovel or similar instrumentality; and a ball bearing interposed between the peripheral vertically disposed face of the supporting element and the adjacent vertical face of the truck frame, said ball bearing forming the sole support and guiding means for the supporting element with reference to the truck and likewise holding the parts against tipping movement with reference to each other.

In testimony whereof I have signed my name to this specification.
